(57) **CLAIM**

The ornamental design for a wind power generation apparatus, as shown and described.

DESCRIPTION

FIG. 1 is a front, right-side, top perspective view of the wind power generation apparatus showing my new design.

FIG. 2 is a rear, right-side, top perspective view thereof;

FIG. 3 is a front elevational view thereof;

FIG. 4 is a top plan view thereof;

FIG. 5 is a right-side elevational view thereof;

FIG. 6 is a left-side elevational view thereof;

FIG. 7 is a rear elevational view thereof; and,

FIG. 8 is a bottom plan view thereof.

The broken lines depict unclaimed portions of the wind power generation apparatus, and thus from no part of the claimed design.
